UNITED STATES PATENT OFFICE

FREDERIK NORMAN LINSTOW, OF BENTON, AND WILLIAM ANDERSON, OF HEBBURN-ON-TYNE, ENGLAND, ASSIGNEES TO A. REYROLLE & COMPANY LIMITED, OF HEBBURN-ON-TYNE, ENGLAND, A COMPANY OF GREAT BRITAIN

SELECTIVE INDICATING MECHANISM

Application filed May 5, 1930, Serial No. 449,991, and in Great Britain June 1, 1929.

This invention relates to indicating mechanism for giving selective indications and although not limited thereto is more especially applicable to indicating mechanism forming part of a remote control system for a number of switches or other apparatus at an electric substation.

The indicating mechanism according to the invention comprises a series of stationary indicators arranged around the circumference of a circle, an actuator common to all the indicators and having a movable actuating member, means for rotating the actuator through a series of positions in each of which the actuating member cooperates with an indicator, and means for operating the actuator in each selected position whereby the actuating member sets the selected indicator in accordance with the condition to be indicated.

When the indicating mechanism is used for giving selective indications of the condition of a number of apparatus one indicator is provided corresponding to each apparatus and means are provided for associating the actuator with the apparatus corresponding to a selected indicator whereby the actuating member operates to set the indicator in accordance with the condition of the corresponding apparatus.

Preferably the movement of the actuator to a selected position causes the establishment of an operative connection between the actuating member and the selected indicator, the operation of the actuator then causing the indicator to move to its indicating position in which it remains when the actuator moves to the next-selected position. Each indicator conveniently has two indicating positions and an intermediate neutral position, the movement of the actuator into a selected position causing the selected indicator to be brought into its intermediate neutral position prior to the operation of the actuating member.

Conveniently a pin is provided on each indicator so that as the actuating member is moved into a selected position, the pin on the selected indicator engages in a shaped slot or groove in the actuating member so

as to provide an operative connection between the indicator and the member.

In a preferred arrangement the actuating member is pivotally mounted on a rotatable bracket and is operatively connected to the 55 armature of an electromagnet constituting the actuator, the armature being carried by the bracket and being movable against the action of a spring in one direction or the other in accordance with the condition to be 60 indicated.

Conveniently the indicators are arranged behind a main indicating panel having windows, one for each indicator, and a chamber is provided behind the panel containing the 65 indicators and one or more lamps, whereby luminous indications are visible through the windows. Preferably each indicator comprises a translucent member rotatably mounted directly behind its window in the panel 70 and bearing suitable indicating markings.

A preferred arrangement of selective indicating mechanism according to the invention will now be described, by way of example with reference to the accompanying drawings, in which

Figure 1 shows a back view of the indicating panel with the indicating mechanism removed,

Figure 2 shows a side elevation, in section 80 on the line 2-2 of Figure 1, of the panel and indicating mechanism, only two indicators being shown for the sake of clearness,

Figure 3 shows a modified form of indicator,

Figure 4 is a back elevation, on an enlarged scale, of the actuator showing one indicator,

Figure 5 is a view of part of the actuator and indicator looking in the direction of the arrows 5-5, Figure 4,

Figure 6 is a similar view to Figure 4 showing the actuator in one of its operative positions,

Figure 7 shows part of the actuator in its other operative position, and

Figures 4a, 6a and 7a show the positions of an indicator, viewed from the front of the panel, corresponding respectively to the positions of the actuator shown in Figures 4, 6 and 7.

As shown in Figures 1 and 2, a main indicating panel A is provided with a series of windows A¹ around the circumference of a circle, and mounted a short distance behind the panel is a frame B carrying bearing blocks B¹ for the spindles of rotatable indicators arranged so that one indicator is mounted behind each window.

In order that the indicators may be illuminated from the chamber formed between the back of the panel A and the frame B, each indicator consists of a disc C of glass having a cone-shaped back C¹ with a ground surface. The disc C is mounted in a metal ring D connected by an arm D¹ to a spindle D² mounted in the bearing block B¹. The arm D¹ is shaped so that the disc C and the spindle D² are coaxial, and rotation of the spindle causes the disc to rotate behind its window A¹.

Indications are provided by comparing the positions of a rod A², mounted in a ring A³ in the window A¹ so that it can be rotated and set by hand, and a straight bar C² painted on the front of the disc C. The rod A² and bar C² are shown in various positions in Figures 4a, 6a and 7a. Preferably the bar C² and the rod A² are painted in contrasting colours, such as red and black, and the bar C² is wider than the rod A² so that when they are in line (Figure 7a) the rod, which may be black, appears flanked by two narrow red lines, whilst in other cases (Figures 4a and 6a) a black and red cross will be visible. In practice a mimic diagram, showing the circuits associated with the switches or other apparatus, the condition of which is indicated by the mechanism, is provided on the front of the panel A. The hand-operated rod A² of an indicator can thus be set, prior to the operation of the associated apparatus, to enable, in the case for example of a switch, the effect of switching changes to be observed before they are carried out and a comparison to be made between the switching conditions which actually exist and those which are desired. The operator first turns the appropriate rod A² to indicate the proposed change so that the difference between the desired conditions and the actual conditions is clearly indicated by a red and black cross, as shown in Figure 6a. As soon as the switch is operated this cross disappears and the indication given consists of a black bar flanked by red lines as indicated in Figure 7a. Any change which takes place, such for example as the automatic tripping out of a circuit-breaker, is immediately and clearly indicated by the appearance of a cross on the panel. It will be appreciated that the hand-operated indicator bars A² ensure that a cross appears at the appropriate window whenever there is a difference between the desired and the actual condition of an indicated piece of apparatus and thus an operator's attention is more posi-

tively directed to such difference than it would be were the hand-operated bars A² omitted.

In an alternative form of indicator shown in Figure 3 the indicator disc consists of a tube of glass C³ having its front face ground and provided with a slot C⁴ by means of which it is supported on a flattened extension D³ on the indicator spindle D². The end of the extension D³ acts as the indicating bar on the disc and the window A¹ is provided with a glass front A⁴ having a narrow bar A⁵ painted thereon and mounted in a rotatable ring A⁶ so that it can be set by hand.

In order to make the indicators visible from a distance the chamber between the panel A and the frame B is illuminated by four lamps E mounted on brackets E¹ arranged round the chamber. Thus, the indicators, as they are made of glass having a ground back surface (or in the case of the indicators shown in Figure 3 a ground front surface) will appear from the front of the panel as luminous discs on which the straight bar markings are easily visible. Preferably the back of the panel A and the front of the frame B are painted white or have polished plated surfaces of nickel, chromium or other suitable metal so as to increase the lighting effect.

Each indicator spindle D² projects at the back of the frame B and has fixed thereto a crank F carrying a pin F¹ which is engaged, as will be described later, by an actuator when it is desired to operate the indicator. In order that the indicator may be retained in a "set" position part of the hub F² of the crank is provided with flattened surfaces for check leaf springs G (most clearly shown in Figure 4) the other ends of which are fixed by a nut and bolt G² to the frame G¹. The flattened surfaces are arranged so that the indicators can be retained "set" by the springs in one or other of two operative positions at right angles to one another or in an intermediate neutral position at 45° to the operative positions.

A common actuator for all the indicators (shown in detail in Figures 4, 5, 6 and 7) is mounted on a shaft H supported in bearings, of which only the bearing B² on the frame B is shown, so that its axis is in line with the center of the circle around which the indicators are disposed. This actuator comprises a bracket J carrying at one end two actuator coils K and K¹ which operate on a common armature L pivoted on the shaft H so that it can be moved to one or other of two operative positions depending upon which of the coils is energized. The armature, which is shown in the operative position in which the coil K¹ is energized in Figure 6, is provided with a tongue L¹ engaged by check leaf springs M, fixed by screws M¹ to the bracket, so as to bias the armature to a central neutral position as shown in Figure 4.

A plate N having a shaped slot N¹ is fastened by screws N² to the other end of the bracket and is formed as shown most clearly in Figure 5. The slot N¹ is shaped with a wide opening so that when an indicator is in one of its operative positions and the shaft H rotates the actuator in the direction of the arrow shown in Figure 4 into its operative position with respect to the indicator (hereinafter termed a selected position), the pin F¹ enters the wide end of the slot N¹ and one of the sides of this slot acts as a guide for the pin to cause the indicator crank F to rotate until the indicator is brought into its neutral position. The position of the straight bar C² on the indicator disc corresponding to this position of the crank F is shown in Figure 4a, it being assumed, in this figure, that the rod A² has been set in the horizontal position. It will be appreciated that since each indicator is brought into a neutral position by the rotation of the actuator before the energization thereof, an indicator must be positively operated by the energization of the actuator. If an indicator were not reset to the neutral position it could remain in one of its indicating positions following engagement with the actuator when it should have been moved to the other position but is not so moved owing to faulty operation of the actuator. Movement of each indicator to the neutral position before the energization of the actuator thus prevents a false indication being given since failure of the actuator to operate leaves the indicator in the neutral position and thereby provides an indication of such failure without giving an incorrect indication of the condition of the associated apparatus.

A plate O is pivoted to the plate N at O¹ and is formed with a shaped slot O² which is similar to the slot N¹ in the plate N and also engages the pin F¹ of each indicator crank as the bracket is rotated. The fixed plate N and the pivoted plate O are arranged so that the slot N¹ of the fixed plate engages the pin F¹ of an indicator before the slot O² of the plate O and so that when the actuator has moved into the selected position as shown in Figure 4 the pin F¹ of the selected indicator is clear of the slot N¹ in the fixed plate N but remains in the narrow portion of the slot O² of the pivoted plate O. The plate O is connected to the armature L by links P and P¹ arranged so that movement of the armature effects a corresponding movement of the plate O in one direction or the other about its pivot O¹.

The energizing circuits of the actuator coils K and K¹ are arranged so that as the actuator is rotated by the shaft H these coils are deenergized prior to the movement of the actuator into a selected position. Thus the armature L and therefore the plate O and its slot are in the neutral position when the

actuator moves into engagement with a selected indicator, which is also moved into the neutral position by the slot N¹ of the fixed plate N.

With the actuator in the selected position one or other of the coils K, K¹ can be energized in accordance with the condition of a selected apparatus or the like of which condition it is desired to retain an indication. Energization of the actuator coil K moves the pivoted plate O into the position shown in Figure 6 and the indicator disc into the position shown in Figure 6a, while the energization of the coil K¹ of the actuator moves the pivoted plate O into the position shown in Figure 7 and the indicator disc into the position shown in Figure 7a. In either case the pivoted plate O moves to carry with it the indicator pin F¹ and thus rotate the crank F against the action of the leaf springs G from the neutral position as shown in Figure 4 through an angle of 45° to the operative position corresponding to the position of the armature L.

The energizing circuits for the coils K, K¹ may be arranged so that a coil which is energized when the actuator is in a selected position is not deenergized until after the actuator has started rotating and the slot O² has moved clear of the pin F¹. Thus when the actuator is rotated to the next selected position the indicator is left in its "set" position and remains in this position until the actuator has been rotated through a complete revolution to engage the same indicator again.

Alternatively the actuator coil may be deenergized before the actuator is moved, in which case the leaf springs G are made appreciably stronger than the leaf springs M¹ which bias the armature L to the neutral position. Hence the indicator will be retained in its operative indicating position by the springs G and the springs M will not act to return the armature L to its neutral position until the slot O² of the plate O has been moved clear of the pin F¹ of the indicator by further rotation of the actuator.

The actuator coils are energized through slip rings R, R¹, R² carried by the shaft H and any convenient means may be provided for insuring that, as the actuator moves into a selected position, the coils K, K¹ are deenergized before the engagement of the slot O² and the indicator pin F. Preferably the operation of the actuator is controlled by a rotary selector (not shown) mounted either directly on or positively geared to the shaft H. The selector may have step-by-step movements imparted to it either by hand or automatically, any suitable form of locking device being provided to ensure that it occupies in turn its correct stepped positions, and the selector may be employed to control the association of the actuator circuits with

the apparatus corresponding to a selected indicator.

This indicating mechanism is particularly suitable for use with a remote control system for a number of switches or other apparatus at an electric substation such for example as that of the kind described in the specification of the U. S. Patent No. 1,820,354, patented August 25, 1931, in the names of Bruce Hamer Leeson and Otis Carter Formby King. In this arrangement a rotary selector is provided at the control station and at the substation. The actuation of a selecting hand switch at the control station causes the selector thereat to make a forward movement equal to half the distance between successive operating positions or steps. The selector or its operating mechanism controls the transmission of a current over pilot wires to the substation which causes the selector thereat to be moved from one operative position to the next and the completion of this movement causes a release current to be transmitted to the control station. The control station selector has meanwhile been maintained locked in its half-notch position and the release current (or more strictly the cessation of such release current) acts to unlock the apparatus and to cause the selector to complete its forward movement to the next position.

The indicating mechanism of the present invention can thus be arranged so that the actuator is mounted on the shaft of the selector at the control station and contacts on the selector (or contacts operated by the selector actuating mechanism) can be arranged so that the actuator coils K, K¹ are deenergized at the time when or shortly before the selector reaches the half-notch position. The substation selector is arranged to associate the actuator coils K, K¹ with the apparatus at the substation corresponding to the selected indicator over pilot wires extending between the two stations so that one or other of the coils is operated to set the selected indicator in accordance with the condition of such apparatus.

This indicating mechanism is also particularly suitable for use with remote control systems having the improved half-notching arrangement described in the specification accompanying the application for Letters Patent of the United States Serial No. 449,968, filed May 5, 1930, in the names of Bruce Hamer Leeson, William Anderson, and Douglas Edward Lambert, and also Serial No. 544,562, filed June 5, 1931, as a divisional application from Serial No. 449,968, and in this case the actuator circuits are conveniently controlled by contacts on the controlling drums which drive the selectors.

When the indicating mechanism is used in conjunction with a remote or other electric control system a mimic diagram representa-

tive of the circuits and apparatus, the conditions of which the indicators record, may be reproduced on the front of the panel so that the bars on the indicators form part of the diagram. Thus, as shown, for example, in dotted lines in Figure 1 the indicators are employed to give an indication of the position of the circuit-breakers in a system of radial feeders, so that, according as a circuit-breaker is closed or open, the bar of the corresponding indicator disc is in line with or at right angles to the diagrammatic circuit on the front of the panel (Figures 6a and 7a).

It will be appreciated that the above description is by way of example only and that modifications may be made in the construction and arrangement of the indicating mechanism within the scope of the invention.

What we claim as our invention and desire to secure by Letters Patent is:—

1. In selective indicating mechanism, the combination of a series of indicators arranged around the circumference of a circle, each indicator having two indicating positions and an intermediate neutral position, an operating crank for each indicator, a pin on the crank, a rotatable bracket, an actuating member having a shaped slot pivotally mounted on the bracket, an electromagnet carried on the bracket, an armature therefor pivoted to the bracket so that it can be moved in either direction from a central position when the electromagnet is energized in accordance with a condition to be indicated, spring means for biasing the armature to the central position, an operative connection between the armature and the actuating member, a driving shaft for rotating the bracket through a series of positions in each of which the pin on the crank of an indicator engages in the slot of the actuating member so as to form an operative connection between the indicator and said member whereby the indicator is moved into the indicating position corresponding to the direction of movement of the armature, and means for moving an indicator into the neutral position operated by the bracket as it moves into the position in which the pin of the indicator engages in the slot of the actuating member.

2. In selective indicating mechanism, the combination of a series of indicators arranged around the circumference of a circle, each indicator having two indicating positions and an intermediate neutral position, an operating crank for each indicator, a pin on the crank, a rotatable bracket, an actuating member having a shaped slot pivotally mounted on the bracket, an electromagnet carried on the bracket, an armature therefor pivoted to the bracket so that it can be moved in either direction from a central position when the electromagnet is energized in accordance with a condition to be indicated, spring means for biasing the armature to the central position,

an operative connection between the armature and the actuating member, a driving shaft for rotating the bracket through a series of selected positions in each of which the pin on the crank of an indicator engages in the slot of the actuating member so as to form an operative connection between the indicator and said member whereby the indicator is moved into the indicating position corresponding to the direction of movement of the armature, a guide member mounted on the bracket and having a slot so shaped that the pin of the crank of each indicator engages in the slot and the indicator is moved into the neutral position as the bracket is rotated into a selected position, and means for retaining each indicator in its indicating position when the bracket is rotated to the next selected position.

3. In selective indicating mechanism, the combination of a series of indicators arranged around the circumference of a circle, each indicator having two indicating positions and an intermediate neutral position, a rotatable bracket, an electromagnet carried on the bracket, an armature for the electromagnet, an actuating member pivoted to the bracket, an operative connection between the armature and the actuating member, a driving shaft for rotating the bracket through a series of selected positions in each of which the actuating member cooperates with an indicator, means whereby each indicator is moved into the neutral position as the bracket is rotated into the selected position in which the actuating member cooperates with the indicator, means for operatively connecting the actuating member to each indicator rendered effective by movement of the bracket into the selected position, whereby energization of the electromagnet in each position of the bracket causes the actuating member to set the indicator in an indicating position in accordance with the condition to be indicated, and means for retaining each indicator in its indicating position when the bracket is moved to the next selected position.

4. In selective indicating mechanism, the combination of a series of indicators arranged around the circumference of a circle, each indicator having two indicating positions and an intermediate neutral position, an operating crank for each indicator, a pin on the crank, a rotatable bracket, an electromagnet carried on the bracket, an armature for the electromagnet, an actuating member pivoted to the bracket, an operative connection between the armature and the actuating member, a driving shaft for rotating the bracket through a series of selected positions in each of which the actuating member cooperates with an indicator, a guide member mounted on the bracket and having a slot so shaped that the pin of the crank of each indicator engages in the slot and the indicator is moved

into the neutral position as the bracket is rotated into a selected position, and means for operatively connecting the actuating member to each indicator rendered effective by movement of the bracket into the selected position whereby energization of the electromagnet in each position of the bracket causes the actuating member to set the indicator in an indicating position in accordance with the condition to be indicated.

In testimony whereof we have signed our names to this specification.

FREDERIK NORMAN LINSTOW.
WILLIAM ANDERSON.
